DESIGN FOR A COSTUMER

John Paul Culpepper and Kenneth C. May,
New Orleans, La.

Application May 25, 1945, Serial No. 119,731

Term of patent 14 years

(CL D33—8)

To all whom it may concern:

Be it known that we, John Paul Culpepper and Kenneth C. May, both citizens of the United States, residing at New Orleans, in the county of Orleans and State of Louisiana, have invented a new, original, and ornamental Design for a Costumer, of which the following is a specification, reference being had to the accompanying drawing, forming part thereof.

We claim:

The ornamental design for a costumer, as shown.

JOHN PAUL CULPEPPER.
KENNETH C. MAY.
